UNITED STATES PATENT OFFICE.

FRANK W. ROLLER, OF PLAINFIELD, NEW JERSEY, ASSIGNOR TO WILBUR B. DRIVER, OF NEWARK, NEW JERSEY.

GLASS-CUTTER.

No. 896,159.

Specification of Letters Patent. Patented Aug. 18, 1908.

Application filed December 14, 1905. Serial No. 291,667.

To all whom it may concern:

Be it known that I, FRANK W. ROLLER, a citizen of the United States, residing at Plainfield, in the county of Union and State of New Jersey, have invented certain new and useful Improvements in Glass-Cutters, of which the following is a full, clear, and exact specification.

My invention relates to glass cutters and particularly to a form in which a heated element is brought into contact with the glass and by the sudden expansion causes the glass to be cut or split on the line of the conductor.

By means of my invention, a simple, durable and convenient form of glass cutter is produced which may be rapidly and easily manipulated.

It is particularly well adapted for cutting off the ends of the glass cylinders formed during the process of manufacture, but is also useful in cutting glass in other forms and for cutting some materials other than those of glass.

My invention will be understood from the following description and accompanying drawings, and is capable of embodiment in various forms of construction. I am therefore, not limited to the particular form shown, and the appended claims will more definitely indicate the scope of my invention.

Figure 1 is a side view of a preferred form of my invention; Fig. 2 is a plan view thereof; Fig. 3 is an end view; Fig. 4 is a part sectional view of some parts for showing the circuit connections being partly broken away to reduce the size of the figure; and Fig. 5 is a side view showing the device applied to a glass cylinder.

The device comprises a handle 1 of wood or other material having extended therefrom two parts 2, 2. Between the extensions 2, 2, is mounted a reel 3 having its bearings in the side strips 4, 4. Secured to the shaft of the reel is a handle 5 and a ratchet wheel 6 both mounted outside of one of the strips 4, there being a washer 7 interposed between the wheel 6 and the side strip. Pivoted on the handle is a latch 8 adapted to engage the ratchet wheel. A spring 9 tends to keep the latch in engagement with the ratchet and a handle 10 on the latch affords a convenient means for moving the latch out of engagement. Between the extensions 2, 2 are fixed two guides of metal 11, 11 each having a slot

12 to receive the ends of a pin 13, upon which a metallic guide wheel 14 is loosely mounted. From each end of the pin 13 extends a spring 15, 15, the opposite ends of these springs being fixed to the guides 11, 11 as shown. On one of the extensions 2 is a block 16 of angular form having pivoted to one side a part 17 with a handle 18. When the part 17 is moved toward the device, it will securely clamp a conductor between its end and the block 16. A conductor 19 is fixed at one end to the reel 3 and may be wound thereon by turning the handle 5. The conductor is preferably an iron wire. It passes from under the reel, over the guide wheel 14 and then after passing around the glass to be cut is brought to the clamp formed by the parts 16, 17.

Current is led through the conductor from the leads 20, and a switch for opening and closing the circuit is conveniently located in the handle 1. This is shown as a hinged wooden block 21 with a spring 22 tending to move it outward and a slotted strip and screw 23 for limiting its outward movement. The hinged block carries a contact 24 which bridges the contacts 25, 25' when the block is moved inwardly. It also carries a contact 26 which engages the contact 27. One of the leads 20 is connected to contact 25 and the other to contact 27. From the contact 25' a lead extends through the handle to the block 16. The contact 26 is electrically connected to the hinge 28, from which latter a lead extends to the guides 11, 11. The handles 5, 10 and 18 may be insulated or of insulating material.

When the device is held in one hand, the handle 10 may be depressed by the thumb which releases the ratchet wheel and the wire 19 may then be freely pulled off the reel and passed around the glass cylinder 29 to be cut. The free end is then secured in the clamp 16, 17. The handle 5 is then turned to take up any slack in the wire, and in doing this the guide wheel 14 is moved down between the guides 11, 11 against the tension of springs 15, 15 to the position shown in Figs. 1 and 3; the latch now serving to prevent backward movement of the reel. Current will now be passed through the conductor by closing the switch in the handle, the path of the current being from one lead 20, through contacts 27, 26 to guides 11, 11, thence by

2 contact of the metal parts and in some degree by the springs 15, 15 to the guide wheel 14 and wire 19, then through the wire to the clamp and block 16 and contacts 25', 24 and 5 25 to the other lead 20. As the conductor becomes heated by the electric current, it will of course expand and the object of the yieldable guide pulley 14, besides securing a suitable tension on the wire, is to take up 10 this expansion automatically and without the necessity of again turning the reel. A slight tapping of the glass may sometimes be necessary to secure its separation.

The advantages of the device in convenience and rapidity of manipulation are apparent.

Having thus described my invention, I declare that what I claim as new and desire to secure by Letters Patent, is,—

20 1. In a glass cutter, the combination of a handle, an electric conductor, a clamp for securing one end of said conductor, and a pawl and ratchet device for regulating the effective length of said conductor, substantially as described.

25 2. In a glass cutter, the combination of a handle, an electric conductor, a clamp for securing one end of said conductor, and a reel for regulating the effective length of said conductor, substantially as described.

30 3. In a glass cutter, the combination of a handle, an electric conductor, a clamp for securing one end of said conductor, a reel for regulating the effective length of said conductor, and means for preventing the reel from turning in one direction, substantially as described.

35 4. In a glass cutter, the combination of a handle, an electric conductor, a clamp for securing one end of said conductor, a reel for regulating the effective length of said conductor, and a ratchet and latch for preventing the reel from turning in one direction, substantially as described.

40 5. In a glass cutter, the combination of a support, an electric conductor, means for securing the ends of said conductor to said support and a yieldable guide over which said conductor passes, substantially as described.

45 6. In a glass cutter, the combination of a support, an electric conductor, means for securing the ends of said conductor to said support and a yieldable guide wheel over which said conductor passes, substantially as described.

50 7. In a glass cutter, the combination of a handle, an electric conductor, a clamp for securing one end of said conductor, means for regulating the effective length of said conductor, and a yieldable guide over which said conductor passes, substantially as described.

55 8. In a glass cutter, the combination of a handle, an electric conductor, a clamp for securing one end of said conductor, a reel for regulating the effective length of said con-

ductor, and a yieldable guide wheel over which said conductor passes, substantially as described.

9. In a glass cutter, the combination of a handle, an electric conductor, a clamp for securing one end of said conductor, a reel for regulating the effective length of said conductor, a ratchet for preventing the wheel from turning in one direction, and a yieldable guide wheel over which said conductor passes, substantially as described. 70

10. In a glass cutter, the combination of a handle, an electric conductor, a clamp for securing one end of said conductor, means carried by said handle for regulating the effective length of said conductor, and a switch for closing the circuit through said conductor, substantially as described. 80

11. In a glass cutter, the combination of a handle, an electric conductor, a clamp for securing one end of said conductor, and a reel for regulating the effective length of said conductor, and a switch for closing the circuit through said conductor, substantially as described. 85

12. In a glass cutter, the combination of a support, an electric conductor, means for securing the ends of said conductor to said support, a yieldable guide over which said conductor passes, and a switch for closing the circuit through said conductor, substantially as described. 90

13. In a glass cutter, the combination of a handle, an electric conductor, a clamp for securing one end of said conductor, means for regulating the effective length of said conductor, a yieldable guide over which said conductor passes, and a switch for closing the circuit through said conductor, substantially as described. 100

14. In a glass cutter, the combination of a handle, an electric conductor, a clamp for securing one end of said conductor, a reel for regulating the effective length of said conductor, a yieldable guide wheel over which said conductor passes, and a switch for closing the circuit through said conductor, substantially as described. 105

15. In a glass cutter, the combination of a handle, an electric conductor, a clamp for securing one end of said conductor, a reel for regulating the effective length of said conductor, a ratchet for preventing the reel from turning in one direction, a yieldable guide wheel over which said conductor passes, and a switch for closing the circuit through said conductor, substantially as described. 110

16. In a glass cutter, the combination of an electric conductor, means for supporting the ends of the effective part of said conductor closely together, and means for automatically taking up any slack in said conductor, substantially as described. 115

17. In a glass cutter, the combination of an electric conductor, a switch for closing the 120

circuit through said conductor, means for supporting the ends of the effective part of said conductor closely together, and means for automatically taking up any slack in said conductor, substantially as described.

18. In a glass cutter, the combination of a handle, an electric conductor, and means carried by said handle for regulating the effective length of said conductor, substantially as described.

19. In a glass cutter, the combination of a handle, an electric conductor, and a reel carried by said handle for regulating the effective length of said conductor, substantially as described.

20. In a glass cutter, the combination of a handle, an electric conductor, means for securing one end of said conductor to the handle, and means for regulating the effective length of said conductor, said latter means being carried by said handle, substantially as described.

21. In a glass cutter, the combination of a handle, an electric conductor, means carried by said handle for adjusting the effective length of said conductor, and a switch carried by said handle for closing the circuit through said conductor, substantially as described.

22. In a glass cutter, the combination of a handle, an electric conductor, means for securing one end of said conductor to said handle, means also carried by said handle for regulating the effective length of said conductor, and means carried by said handle for closing the circuit through said conductor, substantially as described.

In testimony whereof I affix my signature, in presence of two witnesses.
